UNITED STATES PATENT OFFICE.

OSIAS O. KRUH, OF SCHENECTADY, NEW YORK, ASSIGNOR TO GENERAL ELECTRIC COMPANY, A CORPORATION OF NEW YORK.

VAPOR ELECTRIC DEVICE.

1,086,186.

Specification of Letters Patent.

Patented Feb. 3, 1914.

Application filed April 15, 1907, Serial No. 368,423. Renewed March 25, 1912. Serial No. 686,131.

To all whom it may concern:

Be it known that I, OSIAS OTTO KRUH, a subject of the Emperor of Austria-Hungary, residing at Schenectady, county of Schenectady, State of New York, have invented certain new and useful Improvements in Vapor Electric Devices, of which the following is a specification.

The present invention relates to vapor electric devices, and more particularly to rectifiers, lamps, and other apparatus adapted for use on alternating current circuits. Such devices as ordinarily constructed comprise a mercury cathode and one or more anodes. When in use, a vapor arc plays between the mercury cathode and the anode or anodes and a continuous vaporization and condensation of the material of the cathode takes place. When the apparatus embodies a plurality of anodes, there is danger that from time to time one of these anodes may become cathode and thus permit the flow of current through the device in a direction the reverse of that taken by the normal operating current. Several influences may coöperate to change the anode into a momentary cathode, and the present invention has for its object the protection of the anodes from these disturbing influences.

According to this invention, adequate protection of the anodes is secured without entirely inclosing the anodes and without materially constricting the arc path or affecting the efficiency of the apparatus as a rectifier or lamp.

The present invention is not limited to any particular theory, and its scope is defined by the appended claims. I have, however, set forth hereinafter in considerable detail what, at the present time, I consider as the cause of some of the peculiar characteristics of vapor apparatus and I have pointed out how difficulties arising therefrom may be obviated.

My invention will be better understood by reference to the accompanying drawing forming part of this specification, in which the several figures represent operative embodiments of my invention.

Figure 1 is an elevation partly in section illustrating anodes protected by depending bells and shielded from below by a large conical deflector; Fig. 2 shows the anodes provided with separate deflectors; Fig. 3 illustrates a cup-shaped deflector in close

proximity to these anodes; Fig. 4 shows a somewhat similar arrangement with a baffle plate separating one anode from the other.

Each of the vapor devices illustrated in the drawing comprises an evacuated envelop 1 of glass or other suitable material, provided with a vaporizable cathode 2 of mercury, and anodes 3 and 4 of artificial graphite or other suitable material. An auxiliary or starting anode 5 of mercury is also provided and is used in the well-known manner for starting the vapor arc within the rectifier tube. In the drawing, a certain shape of tube is illustrated, but my invention is not limited to the particular conformation shown. The anodes 3 and 4 are provided with suitable leading-in conductors 6 and 7 and are protected, for reasons hereinafter set forth, with depending bell-shaped shields 8 and 9.

In Fig. 1 the anodes are protected by a conical deflector 10 arranged with its concave portion toward the cathode. This deflector may be supported in any convenient manner, as by a platinum wire or rod 11 sealed thereto, and supported by the wall of the envelop.

Fig. 2 illustrates the use of separate deflectors 12 and 13 below the anodes, each consisting of a cone separated from the wall of the envelop but located in the direct path of the arc blast from the mercury cathode.

Fig. 3 illustrates the deflectors 14 and 15 as consisting of cups surrounding their respective anodes and supported on metal wires 16 and 17 sealed in the wall of the envelop.

In Fig. 4, the depending shields 8 and 9 are made somewhat larger than in the other figures and are each provided with an outwardly curved flange 18 perforated to receive bolts 19, by means of which the cup-shaped deflectors 20 may be supported in close proximity to the lower ends of their respective anodes.

When the vapor electric device is in operation, the vapor arc is centered in a very small and intensely bright spot on the cathode surface, and the arc appears to issue from this spot at a high velocity and with a direction substantially perpendicular to that of the cathode surface. A very considerable evaporation of mercury goes on at the cathode surface, no doubt more

than is essential to the transmission of current, and furthermore, a certain quantity of unvaporized mercury seems to be entrained or mechanically carried along with the arc 5 blast. I am convinced that arcing at a rectifier anode may result from contact of this projected mercury with the hot surface of the anodes.

According to my present invention, the 10 deflector or deflectors located between the cathode and the anodes deflect the arc and shield the anodes from excess mercury projected from the cathode. The deflectors also perform another very useful function in that 15 they protect the anodes from ultra violet light and possibly from other forms of energy radiated by the cathode. The formation of a cathode spot on an anode seems, in some way, to be influenced by such emanations from the cathode spot. It will, of course, be understood that the deflectors should be made of some material substantially impervious to these emanations, such, for instance, as glass or metal. The depending bell shaped shields 8 and 9 adequately protect the anodes from mercury falling from above whether the mercury comes from condensations at the top of the tube or is part of that projected from the cathode.

Under some circumstances, I find it desirable to provide a baffle plate 21, as illustrated in Fig. 4. The edges of the plate are preferably disposed close to the side walls of the envelop. This plate serves to prevent 35 the spattering of mercury on an anode when a globule falls from the top of the envelop and strikes the conical surface of the shield surrounding another anode. It also serves to diminish the leakage current between an- 40 odes.

It will be noted that all the modifications illustrated offer an easy path for the vapor arc and that the arc is free to pass between the upper shield and the lower deflector of 45 an anode and thus reach the anode from any direction.

It is evident that various modifications in the embodiment of my invention may be made without departing from the spirit 50 thereof, and that my invention is not limited to the exact details shown and described.

What I claim as new and desire to secure by Letters Patent of the United States, is,—

1. The combination of an evacuated envelop, a vaporizable cathode therein, an anode, a shield for protecting said anode from material falling from above, and a deflector 55 between said anode and cathode and sepa-

rated from said shield by a space through which an arc may pass. 60

2. The combination of an evacuated envelop, a vaporizable cathode therein, an anode, a shield above said anode, and a deflector below said anode separated from said shield by an annular space through which 65 an arc may pass to either side of said anode.

3. The combination of an evacuated envelop, a vaporizable cathode and a plurality of anodes therein, a shield for each anode to protect it from material falling from above, 70 and a deflector interposed between each anode and the cathode and separated from the corresponding shield to allow current flow to the anode.

4. The combination of an evacuated envelop, a vaporizable cathode therein, a plurality of anodes, a shield for each anode for protecting the anode from matter dropping from above it, and a baffle plate interposed 75 between said shields. 80

5. The combination of an evacuated envelop, a mercury cathode and a plurality of anodes therein, shields affording access to said anodes by an annular space for deflecting mercury moving toward said anodes, 85 and a baffle device for preventing mercury from spattering to an anode after impinging on the protective means of another anode.

6. The combination of an evacuated envelop, a cathode and a plurality of anodes 90 mounted therein, a conical shield for each anode to protect it from condensed vaporizable material, and a deflector suspended from said shield and separated therefrom by an annular space. 95

7. The combination of an evacuated envelop, a vaporizable cathode therein, an anode, and a shield interposed between the cathode and the anode, but separated from said anode by an annular space for deflecting 100 the stream of vaporized material away from said anode toward the walls of the container.

8. The combination of an evacuated envelop, a vaporizable cathode therein, an anode situated opposite said cathode, and a deflector interposed between the cathode and the anode for diverting vaporized cathode material away from said anode toward the 105 walls of the container. 110

In witness whereof, I have hereunto set my hand this 12th day of April, 1907.

OSIAS O. KRUH.
